(57) **CLAIM**

The ornamental design for a surveillance camera enclosure, as shown and described.

DESCRIPTION

FIG. 1 is a top, front and right side perspective view of a surveillance camera enclosure showing my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; and, FIG. 8 is a top, rear and left side perspective view thereof. The broken lines shown in the Figures depict portions of the surveillance camera enclosure in which the design is embodied that form no part of the claimed design.
